ATTORNEY

UNITED STATES PATENT OFFICE

OTTO N. GREDELL, OF KANSAS CITY, MISSOURI

METHOD OF FORMING SPIRAL CONVEYERS

Application filed February 17, 1927. Serial No. 169,043.

My invention relates to a method of and apparatus for producing spiral conveyers and has for its principal object to produce a spiral of desired quality at a much lower cost and ease of manufacture than by present methods known in the art.

My method contemplates the forming of flat rings from sheet metal, slitting the rings radially, presenting opposite slotted edges of 10 the complementary rings to each other and securing them together and drawing the ribbon constituted of the connected rings along a shaft or form to produce a true spiral, the planes of the faces of which are at all points 15 throughout the length of the spiral at right angles to its axis.

Heretofore spirals have been formed from disks or rings but the individual rings were stamped to form each a section of the spiral, 20 and the sections assembled one after another on the shaft after which the adjoining ends were riveted together. However, this is a troublesome process requiring much time and does not tend to provide a true continuous 25 spiral with even flights. Spirals have also been drawn from continuous strips of metal but spirals thus drawn lack desirable qualities since the outer edge of the spiral must be drawn out much longer than the inner edge 30 resulting in a feathery outer edge, or if a strip of such thickness is used that the desired outer edge may be produced, the inner edge of the spiral is extremely heavy.

In employing my invention I have been 35 able to produce a spiral conveyer in a way to overcome these difficulties and to provide improved details of structure, as will be described with references to the accompanying drawings wherein:

Fig. 1 is a view of a metal ring such as those from which a spiral of my design is constructed.

Fig. 2 shows metal rings secured together and others in spaced relation.

Fig. 3 is a side view of a machine in process of producing a spiral by my method.

Fig. 4 is a view illustrating a completed spiral.

Fig. 5 is a cross section of a spiral conveyer on the line 5—5, Fig. 4.

Fig. 6 is a detail view of the spiral drawing head as shown in Fig. 3.

Referring more in detail to the drawings:

1 designates a ring cut from sheet metal and having an axial opening 2 adapted to 55 the diameter of the shaft of the spiral conveyer of which the ring is to be a part and having a slit 3 provided preferably by shearing.

The circumference of the opening 2 is preferably equal to the length of the inside edge 60 of a flight of the spiral in its contact with the shaft, and the process of formation of the spiral will not change the radial dimension of the ring.

The ring is provided of such form and dimensions that its thickness at each inner and outer edge is substantially the desired thickness of the spiral.

The adjacent ends of a sheared ring are 70 spaced as at 4 in Fig. 2, and their planes are displaced as at 5 sufficiently to permit the complementary ends of adjacent rings to be welded together as at 6 to form a ribbon of 75 sufficient number of rings to provide a spiral of the desired length.

A shaft or mandrel 8 is provided and the rings so assembled in ribbon form are slipped thereon, the free end of the first ring being secured by a flanged bolt 9 to the shaft, the bolt extending radially of the shaft. The shaft is positioned in a lathe-like machine 10 between centers 11 and 12, the center 12 being the rotating head of the machine and in driving connection with the shaft and is provided with a face plate 14 which through the arm 15 rotates the shaft 8 as in ordinary lathe practice. The machine 10 is provided with a traveling carriage 16 carrying a drawing or die head 17, the carriage being engaged with and propelled by the rotation of a threaded shaft 18 through the gearing 19 at a speed proportionate to the speed of rotation of the shaft 8 for the suitable functioning of the elements of the head as will now 90 be described.

A shaft 20 is positioned longitudinally of the machine below the threaded shaft and rotationally actuated by the gearing 19 and provided with a keyway 21. Slidable on the 100

shaft 20 is a bevel gear 22, keyed to the shaft the bevel gear being carried by the carriage and in mesh with a bevel gear 23 on a counter shaft 24. On the countershaft is a spur gear 25 driving the driven gear 26 on a feed roller shaft 27 mounted in bearings 28 and 29 supported by the carriage.

On the shaft 27 is a pinion 30 in mesh with a pinion 31 on a complementary feed roll shaft 32 also carried by said bearings 28 and 29. The feed rolls 33 and 34 are positioned on the end of the feed roll shafts, for feeding the ribbon through the pairs 35—35', and 36—36' of drawing, forming or shaping rolls 70 or cones secured to the upper part of the driving head and inclined at suitable angles to form the spiral.

The shaping cones are mounted in slideable blocks 36 and 37 actuatable to adjust the pitch 75 of the spiral.

In operating the elements described to produce the result desired, the carriage is so positioned that the feed rolls and the shaping cones may be engaged with the ring ribbon 80 adjacent the point of attachment of the ring with the shaft. The shaft is caused to rotate and the carriage to travel at corresponding speeds, the feed rolls as supported by the carriage extending the ring ribbon along the 85 shaft and thus establishing the pitch of the spiral. At the same time the shaping cones impress upon the sections of ribbon their characteristic influence which confers upon said sections the molded form and nature 90 whereby the spiral produced persists in the conferred spiral form.

I particularly call attention to the function 40 of my described elements, arrangement and process for establishing the said spiral ribbon in a relation of 90 degrees to the shaft, that is, with any cross section of the spiral perpendicular to an intersected tangent of the shaft and coincident with an extended diameter of the shaft and therefore radial thereto 45 as shown in Fig. 5.

What I claim and desire to secure by Letters Patent is:

1. A method of producing a spiral of slitted rings including welding the opposite ends of 50 complementary slit rings together to form a continuous ribbon having continuous plane faces and passing the ribbon through a die to confer the pitch of the spiral.

2. A method of producing a spiral of slitted rings including welding the opposite slitted ends of complementary rings together to form 55 a continuous ribbon and passing the ribbon through forming rolls to mold the material of the ribbon into spiral condition.

3. A method of producing a spiral conveyer 60 of slitted rings including securing the opposite ends of complementary slit rings together to form a continuous helical ribbon, sleeving 65 the ribbon on a shaft and passing the ribbon

through forming rolls for extending the ribbon into desired spiral position.

4. A method of producing a spiral conveyer of a continuous helical ribbon, comprising fixing a free end of the ribbon to a shaft, extending the ribbon along the shaft and coincidentally passing the ribbon through shaping rolls for pressing the portions of the ribbon into permanent condition conformable to the predetermined position of said portions 75 in the spiral.

5. A method of producing a spiral conveyer of a continuous helical ribbon, comprising sleeving the ribbon on a shaft, fixing an end of the ribbon to the shaft, rotating the shaft to pass the ribbon through a moving die to 80 form a spiral about the shaft, and applying pressure to bend the ribbon portion into permanent condition.

6. A method of producing a spiral conveyer comprising sleeving a helical ribbon on a shaft, fixing an end of the ribbon to the shaft, and rotating the shaft to pass the ribbon through rolls traveling longitudinally of the shaft proportionally to the rotation of the shaft 85 to confer the pitch of the spiral.

7. The method of extending a spiral element along a shaft, comprising fixing an end of the element to the shaft and rotating the shaft to pass the element through feeding rolls, traveling longitudinally of the shaft at 90 a rate proportional to the rotation of the shaft to space the flights of the spiral.

8. The method of extending a spiral element along a shaft, comprising fixing an end of the element to the shaft and rotating the shaft to pass the element through feeding rolls traveling longitudinally of the shaft at 95 a rate proportional to the rotation of the shaft to space the flights of the spiral, and rotating the feeding rolls.

9. The method of bending portions of a helical element into permanent condition for constituting flights of a spiral comprising rotating the element, moving successive portions of flights of the element to predetermined pitch position and passing said portions through idling shaping rolls to press said portions into permanent condition.

10. The method of producing a spiral conveyer from a continuous ribbon, comprising sleeving the ribbon on a shaft, fixing an end of the ribbon to the shaft, rotating the shaft to pass the ribbon through shaping rolls and moving the shaping rolls longitudinally of the shaft proportionally to the rotation of the shaft.

11. The method of setting a helically formed element having closely positioned flights in a predetermined spiral position, 115 comprising sleeving the element on a shaft, fixing an end of the element to the shaft, rotating the shaft to pass the element through feeding rolls, moving the feeding rolls longitudinally of the shaft to space the flights, 120 125

rotating the feeding rolls to permit passage
of the element therethrough while retaining
portions of the element in established posi-
tion, and passing the element through idling
5 shaping rolls to impress permanent condition
on the element.

In testimony whereof I affix my signature.
OTTO N. GREDELL.
